UNITED STATES PATENT OFFICE.

KENNETH T. BAINBRIDGE, OF NEW YORK, N. Y., ASSIGNOR TO GENERAL ELECTRIC COMPANY, A CORPORATION OF NEW YORK

LIQUID-CONDUCTOR PUMP.

Application filed May 28, 1926. Serial No. 112,406.

My invention relates to liquid conductor pumps in which the "pinch effect" produced in a liquid conductor of electric current is utilized in a novel manner to move the liquid or to create a pressure therein.

It is well known that when an electric current flows in a conductor a magnetic field is set up around the conductor and there is also a magnetic field in the interior of the conductor. The interior magnetic field is proportional to the current and inversely proportional to the distance from the axis in the case of a cylindrical conductor. It is seen that in the interior of the conductor there is a current flowing and a magnetic field so disposed that it results in forces which tend to reduce the cross section of the conductor, and gives rise to what is known as the "pinch effect." By properly arranging matters the pinch effect in the liquid conductor may vary so as to create pressure differences and a tendency of the liquid to flow in a manner tending to equalize these pressure differences. One application of this principle is found in the mercury ammeter described in the Standard Handbook of Electrical Engineers, third edition, page 92. No extensive utilization of this principle has been made heretofore because of the very low electrical efficiency realized. Thus the ammeter above referred to requires a very heavy current to produce a measurable pressure difference and is not suitable for measuring currents below 200 amperes.

From a purely mechanical standpoint the device would make a very desirable form of pump because it has no moving part.

It is the object of my invention to provide such a pump having an electrical efficiency sufficiently high to make it attractive for many applications.

In carrying my invention into effect I greatly increase the pinch effect for a given current by providing a low reluctance magnetic path for intensifying the interior flux of the conductor. In the preferred arrangement of my invention the reluctance of the flux path is so arranged that the flux lines which are produced solely by the current flowing in the liquid conductor may be said to be eccentric with respect to the conductor, thereby creating a pressure toward one side which is therefore made the outlet of the pump in the manner hereinafter explained in detail.

The features of my invention which are believed to be novel and patentable will be pointed out in the claims appended hereto. For a better understanding of my invention reference is made in the following description to the accompanying drawing in which Fig. 1 represents a cross-section, through a preferred form, of a pump built in accordance with my invention; Fig. 2 is a plan view of the central magnetic plate of the device in which characteristic flux lines have been represented; Fig. 3 represents a cross-section of the pump taken at right angles to the view shown in Fig. 1 and on line 3-3 thereof; Fig. 4 is a perspective view of the pump built as an integral part of a transformer particularly designed to furnish the electric current for operating the pump; Fig. 5 represents curves characteristic of the pump operation; and Figs. 6 and 7 are views of an iron plate for eliminating the bend in the pump outlet.

A cross-section of a simple form of pump is shown in Fig. 1. 10 and 11 represent two electric conductors which may comprise two flat copper plates. These plates are separated by a third plate 12 of magnetic material such as iron. A thin layer of insulation is provided between the iron and copper at one or both surfaces. The iron plate is slotted as shown at 13 in Figs. 2 and 3 from one edge toward the other. When these plates are assembled as shown in Figs. 1 and 3, the slot in the iron plate forms a conduit which communicates with an outlet opening 14 through the copper plate 11 at the inner end of the slot 13. The edges of the iron slot are insulated but the surfaces of the copper plates adjacent the slot are not. Suitable inlet and outlet pipes 15 and 16 are provided for the conduit thus formed. Now if a liquid conductor such as mercury is allowed to fill this slot and the two copper plates are connected across any suitable source of electric current, such as is indicated at 17, a current will flow from one plate to the other through the liquid conductor in the conduit formed in the iron slot 13, as indicated by the arrows in Fig. 3. The flow of current sets up a magnetic flux across the liquid conductor at substantially right angles to the direction of current flow and due to the nature of the flux path formed by the slotted plate 12 these flux lines take the eccentric form indicated

by the closed lines in Fig. 2. It is seen that the local magnetic flux is not allowed to scatter but is concentrated due to the presence of the iron and passes normally across the conductor and completes its path by traversing the iron at the inner end of the slot. Thus we have a concentrated magnetic field across and through the liquid conductor.

Disregarding for the moment any disturbance which might be produced by eddy current phenomena when the mercury is flowing, the intensity of this field varies directly with the distance from the inner end of the slot and the strength of the current and inversely as the width of the slot. It will be seen that the density of the transverse flux at any point in the slot is practically determined by the slot width and the total current flowing in the slot between the point considered and the inner end of the slot, and is thus a maximum at the inlet end of the slot and zero at the extreme outlet end of the slot. As this flux passes normally across the slot and the direction of current flow is substantially or actually perpendicular to this magnetic field, forces result on the liquid conductor which manifest themselves as hydrodynamic pressure at the inner or outlet end of the slot, which makes of this device a liquid conductor pump of remarkable efficiency as compared to prior arrangements, utilizing the so-called "pinch effect".

A number of practical considerations enter into the proper design of such a pump. The first consideration is the requirement of a heavy current of low voltage. This current may be either direct or alternating. If direct, the flux lines about the liquid conductor will always be in one direction, and if alternating, the flux lines will reverse in direction with the reversal of the current, but the pressure will always be in the same direction.

Fig. 4 shows one practical embodiment of the invention where the liquid conductor and the communicating electrodes are contained in the secondary circuit of a transformer. 17' represents the primary winding of the transformer made up of a number of turns. 18 represents the magnetic core of the transformer and 19 a single turn secondary winding. This secondary winding is virtually a short-circuited secondary made up of the U-shaped conductor 20 and a unit substantially similar to that shown in Fig. 1 comprising the two copper plates 10 and 11 separated by the slotted iron plate 12. The iron plate is insulated from the circuit so that the secondary current of the transformer can only flow through the liquid conductor contained in the conduit formed in the iron plate. If a 5 ampere 50 turn primary winding is used approximately 250 amperes will flow in the secondary circuit.

The reactance of the secondary circuit is negligible, as compared to the resistance, which is practically all made up by the resistance in the mercury, and the slot flux is in phase with the current. As a consequence the power factor of the device will be relatively high.

In some cases it may be important to make the device independent of temperature changes. The temperature coefficient of mercury is very low as compared to copper and since the mercury makes up the greater part of the resistance of the secondary circuit, the temperature coefficient of the combined circuit will always be low. However, if desired, one of the plates 10 or 11 may be made of a conducting material having a high negative temperature coefficient of resistance and of such ohmic resistance as to make the resistance of the circuit independent of temperature changes. If the pump is to produce a flow of mercury as distinguished from maintaining a certain pressure with little flow and is to be independent of temperature changes, attention should also be given to the fact that the viscosity of mercury decreases with temperature rise and consequently will flow easier through the pump circuit as the temperature increases. This may also be taken care of in the proper design of the secondary circuit such that the various changes due to temperature will balance each other leaving the operation of the device independent of temperature changes if that is desired.

In order to provide a good contact between the copper and mercury and not allow the mercury to amalgamate with the copper, the latter is preferably coated with a surface that does not amalgamate but still presents a good contact, or a contact which is wet by the mercury. A flash of platinum on the copper surface normally in contact with the mercury will prevent amalgamation and present a perfect contact between the copper and mercury. Low permeability steel is also satisfactory for this coating.

For the insulation between the copper and iron plates, sheets of mica cut the same size as the iron plate and attached thereto by temperature resisting enamel may be used. To insulate the iron from the mercury the slot may be coated by a suitable enamel. When thus assembled the device should be thoroughly baked so that no bubbles will develop later when in use. The pump circuit should of course have as few sharp turns and restrictions as possible. The proper shaping of the outlet, which should be in general of larger area than the slot itself, should be such as to offer the least resistance to the flow therethrough. To eliminate a bend at the outlet end of the slot the outlet may be made straight through the iron plate increased at this point to retain the low re-

luctance flux path as indicated in Figs. 6 and 7. Figs. 6 and 7 correspond to the views of the iron plate shown in Figs. 2 and 1 respectively. When mercury flows through the slot, a voltage is induced in the mercury opposing the flow of current. In such cases it may be advisable to shape the slot such that the induced voltage along the slot is the same at all points. This can be accomplished by designing the slot such that Bv is a constant where B equals the flux density crossing the slot at any point and v equals the velocity of flow at the same point. When this is done there are no local circulating currents in the copper and mercury that would reduce the efficiency and disturb the flux distribution.

The flux density of the transformer core is low and the core may be of small area. The core loss will be negligible. The transformer core and the iron plate 12 may be of laminated material in accordance with good practice. The device will be substantially independent of frequency changes if the magnetic circuits are operated below saturation.

In Fig. 4 I have shown various curves obtained by plotting the static pressure head in centimeters of mercury against the corresponding values of current in amperes in the mercury slot to obtain such pressures. Curves A, B and C represent the results of actual tests of a device such as is represented in Fig. 4 using 60, 40 and 25 cycle alternating current respectively. Curve E represents the calculated theoretical pressure obtainable with a device of the same dimensions as that used for the test curves, and curve F represents the calculated theoretical pressure obtainable at the center of a circular mercury conductor of the same area as that used in the tests but without the use of iron to concentrate the flux.

The mathematical calculations for obtaining curves E and F are somewhat involved and are not reproduced here. In general the increase in pressure for my design of pump over the ordinary pinch effect is theoretically $\frac{2\pi d}{w}$ where d equals the effective length

of the slot and w the width. In general $\frac{d}{w}$ should be large for high pressure. In the apparatus built and tested it was calculated that the pressure should be increased 84 times over that theoretically obtainable without flux concentration. 60% of this gain was actually realized in the apparatus when tested, the difference between the curves A, B, C and the calculated value of pressure represented by curve E, being due to eddy current losses, flux leakage, etc. The tests prove the correctness of the principle involved and show a remarkable gain in efficiency for my apparatus over previous de-

vices utilizing the "pinch effect". When a higher pressure is desired than that which is practicable to obtain by a single unit or pump such as has been described, two or more such units may obviously be connected in series.

There are many applications where such a pump may be utilized. The fact that there are no moving parts such as valves, pistons, bearings, etc., makes this type of pump very attractive. No lubrication is required. There is no wear of rubbing parts. There is no noise. The action may be made independent of temperature and frequency variations so as to make the pump suitable for accurate relay purposes. Ordinarily a liquid pump requires two elements, the pump itself, and some kind of a motor for driving the pump. In the present case the two are combined in a single unit in a very simple and compact manner, it being required however that the liquid shall be an electric conductor.

In accordance with the provisions of the patent statutes, I have described the principle of operation of my invention, together with the apparatus which I now consider to represent the best embodiment thereof; but I desire to have it understood that the apparatus shown and described is only illustrative and that the invention may be carried out by other means.

What I claim as new and desire to secure by Letters Patent of the United States, is:

1. A fluid conductor pump comprising an electric circuit having a portion thereof made up of a fluid conductor, a conduit with inlet and outlet openings for such fluid conductor, and magnetic means conductively excluded from said electric circuit and magnetized solely by the flux set up by the current flowing in said conductor for directing the flux, due to current flowing in said conductor, through and about said conductor so as to produce points of different flux intensity therein at the inlet and outlet of said conduit.

2. A liquid conductor pump comprising an electric circuit having a portion thereof made up of a liquid conductor, a conduit for such liquid conductor, magnetic means magnetized solely by the flux set up by the current flowing in said conductor and positioned closely adjacent the liquid conductor portion of said electric circuit, but not conductively included therein, for producing a low reluctance flux path guiding the flux produced by the current flowing in said conductor, across said conduit at substantially right angles to the direction of current flow therethrough and with varying intensity at different points therein, and inlet and outlet openings in said conduit at points of different flux intensity therein.

3. A liquid conductor pump comprising an electric circuit having a portion thereof

4
made up of a liquid conductor, a conduit for such liquid conductor, magnetic means magnetized solely by the flux set up by the current flowing in said conductor and insulated from said electric circuit for producing a low reluctance flux path guiding the flux set up by the current flow in said conductor across said conduit at substantially right angles to the direction of current flow therethrough and with varying intensity across said liquid conductor, an inlet for said conduit at a point of maximum flux intensity in said conduit and an outlet for said conduit at a point of minimum flux intensity of said conduit.

15 4. A liquid conductor pump comprising an electric circuit having a portion thereof made up of a liquid conductor, a conduit for said liquid conductor, magnetic means magnetized solely by the flux set up by the current flowing in said conductor and insulated from said electric circuit for producing a low reluctance flux path partially surrounding said liquid conductor such that the flux produced by current flowing in said conductor varies in intensity at different points in said conductor and inlet and outlet openings into said conduit at points of different flux intensity therein.

5. A fluid conductor pump comprising a 30 conduit of substantially rectangular cross section, two opposite sides of which are formed of electric conductors and the other sides of which are enclosed by, but insulated from, a substantially U-shaped magnetic structure, said magnetic structure being magnetized solely by the flux set up by the current flowing in said conductor, an inlet for said conduit at the open end of said U-

shaped magnetic structure, an outlet for said conduit at the closed end of said magnetic structure, a liquid conductor in said conduit, an electric circuit, and connections for including said two electric conductors and said liquid in series relation in said circuit.

6. A liquid conductor pump comprising an 45 electric circuit formed by substantially a short-circuited secondary of a transformer, a portion of said circuit being made up of a liquid conductor, a conduit with inlet and outlet openings for said liquid conductor, and magnetic means magnetized solely by the flux set up by the current flowing in said conductor for directing the flux produced by the current flowing in said conductor, so as to produce points of different flux intensity in said liquid conductor at the inlet and outlet points.

7. A fluid conductor pump comprising an electric circuit having a portion thereof made up of a fluid conductor, a conduit with 60 inlet and outlet openings for said fluid conductor, and magnetic means magnetized solely by the flux set up by the current flowing in said conductor and insulated from said electric circuit for directing the flux, due to current flowing in said conductor, so as to produce points of different flux intensity in the conductor at the inlet and outlet of said conduit, the combined temperature coefficient of said electric circuit being such 65 as to make the operation of said pump substantially independent of temperature changes.

In witness whereof, I have hereunto set my hand this 26th day of May 1926.

KENNETH T. BAINBRIDGE.
